UNITED STATES PATENT OFFICE.

FRANK B. HINKSON AND WILLIAM I. CRAWFORD, OF NEW CASTLE,
PENNSYLVANIA.

PLUMB-LEVEL.

SPECIFICATION forming part of Letters Patent No. 633,589, dated September 26, 1899.

Application filed December 2, 1897. Serial No. 660,494. (No model.)

To all whom it may concern:

Be it known that we, FRANK B. HINKSON and WILLIAM I. CRAWFORD, residing at New Castle, in the county of Lawrence and State 5 of Pennsylvania, have invented a new and useful Plumb-Level, of which the following is a specification.

This invention relates to improvements in plumb-levels; and the object thereof is to provide a simple construction of level in which the pointer is visible and its position ascertainable from the top and sides of the level, so that a plumb-level is provided which is very convenient in use.

With the above object in view the invention consists of the stock having a transversely-extending passage in which a cylindrical open-ended casing of transparent material is positioned, a ring located centrally 15 within the casing and V-shaped in cross-section, with graduations on the inner and outer surfaces of its sides, and crystals positioned upon the respective sides of the stock and closing the open ends of the cylinder, said crystals 20 having central bearings on their inner sides to receive the ends of an arbor, said arbor having a plumb-bob located centrally thereon and having its ends forked or bifurcated, with the forks thereof engaging the inner faces of 25 the V-shaped ring, the forks at one end having arrow-heads and those at the opposite end provided with weights, said ring being slotted at the point of the V at its upper end, so that a portion of the plumb-bob is visible through 30 a slot formed in the top edge of the stock and communicating with the transversely-extending 35 passage.

The invention further consists in the improved construction, arrangement, and combination of parts hereinafter fully described and afterward specifically pointed out in the claims.

In order to enable others skilled in the art to which our invention most nearly appertains to make and use the same, we will now proceed to describe its construction and operation, having reference to the accompanying drawings, forming part of this specification, in which—

Figure 1 is a perspective view of a plumb-level embodying our invention. Fig. 2 is a

top plan view of the same. Fig. 3 is a vertical longitudinal sectional view. Fig. 4 is a vertical transverse sectional view. Fig. 5 is a perspective view of the arbor and plumb-bob. 55 Fig. 6 is a perspective view of the cylindrical casing with the V-shaped ring positioned therein. Fig. 7 is a perspective view of one of the crystals. Fig. 8 is a perspective view of the V-shaped ring. 60

Like letters of reference mark the same parts wherever they occur in the various figures of the drawings.

Referring to the accompanying drawings, A indicates the stock, which is provided with 65 a transversely-extending passage to receive the open-ended cylindrical casing B, which is formed of glass or other transparent material. Positioned centrally within the casing and beneath the vertical slot C, extending inwardly 70 from the upper edge of the stock and communicating with the transversely-extending passage, is a V-shaped ring D, each of the sides of the ring being graduated on the inner and outer surfaces thereof, as illustrated 75 at a and b, respectively. The sides of the V at their outer edges are formed with the flanges C, which engage the inner wall of the casing, while said ring is slotted at the point of the V, as illustrated at E, said slot being 80 located beneath the vertical slot C of the stock.

F are crystals which are secured upon opposite sides of the stock and close the open ends of the cylindrical casing, said crystals being provided on their inner sides with the 85 central bearings G to receive the ends of the arbor H.

Mounted centrally upon the arbor is the plumb-bob I, which rotates on the inner side of the point of the V-shaped ring and at its 90 upper end is bifurcated, with the bifurcations e and f moving upon the inner sides of the respective sides of the V-shaped ring and provided with arrow-heads, which coact with the graduations on the sides of said V. The opposite end of said plumb-bob is provided with the forks J and K, which are also bent to move on the inner surfaces of the respective sides of the V and are provided at their extremities with the balls or weights L. 95

In operation the plumb-level is used as is an ordinary level, and the position of the

plumb-bob may be ascertained by glancing in through either one of the crystals, the pointer *e* being visible from one side and the pointer *f* from the opposite side of the stock.

5 The position of the plumb-bob may be also ascertained by looking through the vertical slot *C* of the stock, as the slot in the ring is of sufficient width to render a portion of each pointer visible therethrough and the position

10 thereof in relation to the scale upon the upper surfaces of the sides of the V-shaped ring readily ascertained.

From the above description it will be seen that we have produced a very simple construction of plumb-level which is very convenient in operation, inasmuch as the position of the plumb-bob may be readily ascertained from either the sides or top thereof.

While we have illustrated and described 20 the best means now known to us for carrying out our invention, we do not wish to be understood as restricting ourselves to the exact details of construction shown and described, but hold that any slight changes or variations 25 such as might suggest themselves to the ordinary mechanic will properly fall within the limit and scope of our invention.

Having thus fully described our invention, what we claim as new, and desire to secure by 30 Letters Patent of the United States, is—

1. In a plumb-level, the combination with the stock provided with a transversely-extending cylindrical passage of transparent plates closing the ends of said passage, said plates being provided with bearings on their inner sides, an arbor mounted in said bearings and carrying the plumb-bob *I* in a ring positioned in said cylindrical casing consisting of one piece and V-shaped in cross-section and provided with graduations upon the inner and outer surfaces of its respective sides, and also slotted in line with the slot of said stock, substantially as described.

2. In a plumb-level the combination with the cylindrical casing in the stock of the transparent ends provided with arbor-bearings into which the arbor-points of the plumb-bob are adapted to fit, of a one-piece ring provided with diverging flanges and slotted in line with the slot in the stock, substantially as de- 45 50 scribed.
